UNITED STATES PATENT OFFICE.

DAVID EMERICK, OF TOLEDO, OHIO.

DISPLAY-MODEL.

SPECIFICATION forming part of Letters Patent No. 395,124, dated December 25, 1888.

Application filed March 9, 1888. Serial No. 266,749. (No model.)

To all whom it may concern.

Be it known that I, DAVID EMERICK, a citizen of the United States, residing at Toledo, in the county of Lucas and State of Ohio, have invented certain new and useful Improvements in a Display-Model; and I do hereby declare that the following is a full, clear, and exact description of the invention, which will enable others skilled in the art to which it applies to make and use the same, reference being had to the accompanying drawings, and to the letters of reference marked thereon, which form part of this specification.

My invention relates to display-models for use in exhibiting wares—such as harness, robes, saddles, and like articles—and has for its object the construction of models of sufficient strength to withstand the great strain incident to a sudden gust of wind against the side thereof, or in moving the same from one place to another.

A further object is to so arrange the parts that each one-half section of the form or shell can be constructed as a full representation of the side to which it pertains, thereby obviating the use of sectional parts, the object being to form the shell of wood pulp, wood fiber, paper fiber or pulp, tar-board, rubber, or, if desired, of sheet metal, by pressing the same into the desired shape between dies in such finished state as to obviate the necessity of expensive fitting or supplemental pieces.

A still further object is to provide for portability by forming casters upon the feet, by which the model may be moved when desired.

In the class of inventions to which mine belongs the great difficulty heretofore has been in forming the model of sufficient strength to support the weight of the body upon the legs without danger of fracture thereof. The body being of an area to present a large surface against which a gust of wind can bear with great force causes a heavy strain upon the legs, and the frequent necessity of moving the model causes the body to sway more or less upon the leg-supports.

The invention consists, chiefly, in forming the legs of a length and shape to extend to the interior of the model and strongly bolting the same together, thereby forming a firm support for the outer shell or form, also in constructing each side of the form or shell of a

single piece and securing the same to the legs, the whole being supported upon casters, which may extend through the base-board of a truck, or the truck may be omitted and the model moved upon the casters.

In the drawings, Figure 1 is a side elevation of a display-model of a horse. Fig. 2 is a front and Fig. 3 a rear view. Fig. 4 is a front and Fig. 5 a rear view of a pair of front legs strongly bolted together. Fig. 6 is a front and Fig. 7 a rear view of a pair of hind legs secured together by bolts. Fig. 8 is a detail view of a filling-piece.

Like letters of reference indicate like parts.

A A designate the front legs, each formed with an upper arched portion, B, having legs C perforated to receive a bolt, D, by which the pair may be securely bolted together and the fastenings concealed by the outer covering.

E E designate the hind legs, each upper portion of which is arched to meet at the center, and are provided with lugs F, perforated to receive a bolt, G, by which the legs are firmly secured.

The contour of the arch of each set of legs is such as to represent the form of the part of the model to which it belongs, the arch of the front legs being of greater width than that of the pair of hind legs, to correspond with the greater width of the breast.

H designates casters permanently attached to each foot, whereby the model may be moved, or, if it is desired to mount the model upon trucks, the casters may be inserted in suitable perforations in the base-board and serve as a fastening, or may pass entirely through and serve as casters to the truck.

K K represent the half-sections of the outer shell, which may be formed of any suitable plastic material or metal capable of being formed into the desired shape by dies. Each section is formed to correctly represent the one-half of the body of the model, and is seated upon shoulders L of the legs and securely fastened thereto in any preferred manner, after which filling-piece M is secured to the rear part to form a smooth exterior for the crotch portion, and the whole is then painted and finished in any desired color, or, if desired, the body portion may be covered with canvas and painted the color desired.

The legs are designed to be made of cast, malleable, or any metal having the requisite rigidity to sustain the strain.

The final finish of eyes, ears, mane, and tail are completed in harmony with the color of the model, the tail and ears being inserted in perforations in the body of the model.

While I have shown and described the model of a horse as pertaining to one branch of trade—as the display and sale of saddlery goods and harness—the mode of constructing the parts is equally well adapted to the formation of models of animals of any genus suggestive of a particular branch of trade.

It will be seen that the model thus constructed is of but few parts, and obviates the necessity of expensive fitting of sectional parts, and that the leg-sections form strong braces to support the form.

I am aware that it is not broadly new to construct a display-model with a metal frame and an outer shell, the constructions heretofore manufactured being deficient in the essential particulars sought to be covered by the present claims.

What I claim, and desire to secure by Letters Patent, is—

1. A display-model having the configuration of an animal, the supporting-legs of which have their upper ends arched toward each other and secured together, said arching keeping the body portion within its center of gravity, substantially as described. 30

2. A display-model representing the configuration of an animal, a body portion or shell 35 composed of two longitudinal side sections, and a filling or buttock piece, substantially as described.

3. A display-model representing the configuration of an animal having fore and hind 40 legs arched and meeting at their upper ends, a body portion composed of two longitudinal sections, with a rear filling or buttock piece, substantially as described.

In testimony that I claim the foregoing as 45 my own I hereby affix my signature in presence of two witnesses.

DAVID EMERICK.
